DISPENSING FAUCET FOR A COFFEE URN OR THE LIKE

Martin J. Lewis, Morrisville, Pa., assignor to Franklin Machine Products Co., Inc., Trenton, N.J., a corporation of New York

Application April 15, 1959, Serial No. 55,514

Term of patent 14 years

(Cl. D2—3)

Fig. 1 is a front elevational view of a dispensing faucet for a coffee urn or the like, showing my new design;

Fig. 2 is a side elevational view thereof; and

Fig. 3 is a top plan view thereof.

I claim:

The ornamental design for a dispensing faucet for a coffee urn or the like, substantially as shown.
